UNITED STATES PATENT OFFICE.

FREDERICK L. HUMESTON, OF NEW HAVEN, CONNECTICUT, ASSIGNOR TO WINCHES-
TER REPEATING ARMS COMPANY, OF NEW HAVEN, CONNECTICUT, A CORPORATION
OF CONNECTICUT.

HAND LAMP.

Application filed October 29, 1926. Serial No. 144,927.

My invention relates to battery hand lamps of the type including a casing for the battery, a lamp bulb, switch mechanism for completing the electric circuit through the bulb, and a bottom end cap for closing the bottom end of the casing and holding the battery in proper position within the casing. My invention relates particularly to the provision of improved means for supporting a spare lamp bulb within the bottom end cap of the battery casing, the bulb being supported in such a way that it is clearly exposed to view whenever the end cap is removed.

It has been proposed heretofore to provide means for carrying one or more spare lamp bulbs within a battery hand lamp, so that whenever the bulb which is connected in circuit with the battery becomes broken or burned out, it is merely necessary to remove the useless bulb and insert one of the spare lamp bulbs in its place, thus rendering the lamp fit for use again.

According to my invention, a spare lamp bulb can be carried within the bottom end cap, and this without impairing the operation of any parts which are normally enclosed within this end cap. It is common practice to provide a spring member within the bottom end cap adapted to press against the bottom of the battery so as to hold the battery firmly against a contact member arranged to engage the central electrode of the battery at the forward end of the casing. I have found that it is possible to mount a spare lamp bulb within the bottom end cap without interfering with the action of the spring member against the bottom of the battery, and in fact, my invention contemplates the mounting of the spare lamp bulb on the spring member in such a manner that the spring acts as a buffer between the lamp bulb and the end cap. The lamp bulb is preferably supported out of contact with any portion of the end cap. The spare lamp bulb is thus fully protected against breakage at all times, even though the hand lamp may be dropped or otherwise roughly handled.

The mounting of the spare lamp bulb on the spring member within the bottom end cap has the distinct advantage of clearly exposing the spare lamp bulb to view whenever the end cap is removed for any reason,

such as the replacement of the battery. The parts can be constructed and arranged in such a manner that when the end cap is removed, the lamp bulb is carried forward by the spring member until it extends beyond the open end of the cap. In this manner the owner of the hand lamp is periodically reminded of the fact that he has a spare lamp bulb ready for use in any emergency.

The various objects and advantages of my invention, some of which have been mentioned above, will be more apparent upon considering the following detailed description, which is to be taken in conjunction with the accompanying drawings, in which I have illustrated one embodiment of my invention.

In the accompanying drawings, Fig. 1 is a longitudinal section view of a portion of a battery hand lamp illustrating one embodiment of the invention;

Fig. 2 is a longitudinal section view of a portion of a battery hand lamp illustrating the same embodiment of the invention as applied to a hand lamp having a battery casing of insulating material;

Fig. 3 is a transverse section view of a bottom end cap provided with my improved bulb support; and

Fig. 4 is a sectional elevation taken on line 4—4 of Fig. 3, showing a construction of the bulb support.

In the embodiment of the invention illustrated in Fig. 1, the battery casing 1 is of metal, and contains a battery 2 of dry cells arranged end to end in series connection, in accordance with standard practice. A bottom end cap 3 closes the bottom end of the casing 1, thereby enclosing and concealing the bottom end of the battery 2. The end cap 3 carries a spring member 4 which is preferably, though not necessarily, of the coil type shown in the drawings. A spare bulb support 5 is yieldingly supported within the end cap 3, preferably by the spring member 4. The bulb support may be of any desired form, but I prefer to make this support out of a single piece of metal which can be fixed to the spring member 4 in any suitable manner, as by means of a central rivet 6.

The particular bulb support illustrated in the accompanying drawings comprises a single piece of metal having a base portion 7 having a central aperture adapted to re-

ceive the rivet 6. The bulb support is also provided with two side members 8 and 9, from which a pair of oppositely arranged tangs 10 and 11 may be struck inwardly so as to form flexible arms adapted to engage the threaded base 12 of the lamp bulb. The support can also be provided with a bent up end member 13, adapted to engage the bulb and prevent accidental longitudinal displacement of the bulb. The member 13 is arranged at one end of the bulb support and the other end of the support is preferably left open so as to provide ample space for taking hold of the threaded end of the bulb to remove the same from the support. In fact, it is desirable to cut away a portion of the base 5 of the bulb support, as indicated at 14 in Fig. 3, so as to make the lamp bulb even more accessible.

20 The side portions 8 and 9 of the bulb support are preferably provided with curved surfaces, such as that indicated at 15, extending out beyond the lamp bulb and adapted to engage the bottom of the battery tube. These side portions thus serve to space the lamp bulb apart from the bottom of the battery, and the curvature of the side portions permits the bulb support to assume an easy position against the battery. 30 It will be appreciated that the spring member 4 yieldingly presses the bulb support against the bottom of the battery, thus producing substantially the same effect upon the battery as though the bulb support were 35 not present. The battery is held in proper position within the casing by the action of the spring member, and the lamp bulb is yieldingly supported within the bottom end cap out of contact with the battery and out of contact with this cap. Furthermore, whenever the bottom end cap is removed in order to replace the battery or for any other reason, the spring member serves to carry the spare bulb forward so that it is clearly 45 exposed to view, as illustrated in Fig. 4. In this way, the owner of the hand lamp is periodically reminded of the fact that he has a spare lamp bulb available for use whenever the bulb connected in the battery 50 circuit burns out. This is a distinct advantage, because many of the spare lamp bulb supports heretofore employed have been constructed and arranged within the casing in such a manner that the owner of the lamp 55 seldom has occasion to notice the spare lamp bulb and may forget that he has one available for an emergency.

The embodiment of the invention illustrated in Fig. 2 is exactly the same as that 60 illustrated in the other figures of the drawing. Fig. 2 merely illustrates the application of the invention to a hand lamp having a battery casing consisting of insulating material, as distinguished from the metal casing 65 1, shown in Fig. 1. The insulating cas-

ing 1' of Fig. 2 is provided with a screw-threaded metal ring 16 adapted to receive the end cap 3, the end cap being of the same construction as that shown in Fig. 1. Where an insulating battery casing is employed, it 70 is necessary to provide some means for establishing a connection between the switch mechanism (not shown) and the bottom electrode of the battery. In Fig. 2, this is accomplished by providing a metal conducting strip 17 which makes electrical contact with the ring 16. The connection is completed to the bottom electrode of the battery through the end cap 3, the spring member 4 and the spare bulb support 5. 75

It is to be understood that my invention is not limited to the particular embodiment illustrated and described, but includes such modifications thereof as fall within the scope of the appended claims. For example, the details of the spare bulb support may be changed without sacrificing all of the advantages of my invention, and the same is true of the manner in which the spare bulb support is mounted within the bottom end 80 cap.

I claim:

1. In a hand lamp, the combination of a casing, a battery therein, an end cap for the casing, a spring member within said end cap, and a spare bulb support having a base portion fixed to said spring member and two side portions adapted to engage the battery and to space the spare bulb apart from the battery, the said side portions 100 having curved portions for engaging the battery.

2. In a hand lamp, the combination of a casing, a battery therein, an end cap for the casing, a spring member within said end cap, and a spare bulb support fixed to said spring member and having integral side portions provided with means integral therewith for gripping the base of the spare bulb. 105

3. In a hand lamp, the combination of a casing, a battery therein, an end cap for the casing, a spring member within said end cap, and a spare bulb support having a base portion fixed to said spring member and side portions adapted to engage the battery and having means integral therewith for gripping the base of a spare bulb, and the said support having an end portion for preventing accidental longitudinal displacement of the bulb. 115

4. In a hand lamp, the combination of a casing, a battery therein, an end cap for the casing, a spring member within said end cap, and a spare bulb support having a base portion fixed to said spring member and side portions adapted to engage the battery and having means integral therewith for gripping the base of a spare bulb, and the said support having an end portion for preventing accidental longitudinal displacement of 120 130

the bulb, a part of the base portion of the bulb support being cut away to facilitate removal of the bulb from the support.

5. In a hand lamp, the combination of a casing, a battery therein, an end cap for the casing, a spring member within said end cap, a spare bulb support comprising a base portion fixed to said spring and a wall portion integral with said base portion and
10 adapted to engage the battery, and means on said base portion for gripping the base of a spare bulb, said wall portion having an opening therein through which the end of the spare bulb protrudes.
- 15 6. In a hand lamp, the combination of a casing, a battery therein, an end cap for the casing, a spiral coiled spring having the large end thereof fixed within said end cap, a spare bulb support comprising a base portion fixed to the small free end of said spring and a wall portion integral with and
20 extending upwardly from said base portion,

the upper edges of said wall portion being adapted to engage the battery, and means on said base portion within said wall portion 25 for gripping the base of a spare bulb, said wall portion having an opening therein through which the end of the spare bulb protrudes.

7. In a hand lamp, the combination of a 30 casing, a battery therein, an end cap for the casing, a spring having one end thereof fixed within said end cap, a spare bulb support comprising a base portion fixed to the free end of said spring and a wall portion 35 extending away from said base portion and adapted to engage the battery, and means on said base portion within said wall portion for gripping the base of a spare bulb, whereby both said bulb, and said entire bulb support are located above the upper free end of said spring.

In testimony whereof I affix my signature.
FREDERICK L. HUMESTON.
